CLAIM

The ornamental design for a faceted assembly, as shown and described.

DESCRIPTION

FIG. 1 is a perspective view of a faceted assembly in accordance with our new design;

FIG. 2 is a top plan view thereof;

FIG. 3 is a side elevation view thereof, the opposing side being a mirror image thereof;

FIG. 4 is an end elevation view thereof, the opposing end being a mirror image thereof;

FIG. 5 is a bottom plan view thereof;

FIG. 6 is a perspective view of a faceted assembly in accordance with our new design;

FIG. 7 is a top plan view thereof;

FIG. 8 is a side elevation view thereof, the opposing side being a mirror image thereof;

FIG. 9 is an end elevation view thereof, the opposing end being a mirror image thereof;

FIG. 10 is a bottom plan view thereof;

FIG. 11 is a perspective view of a faceted assembly in accordance with our new design;

FIG. 12 is a top plan view thereof;

FIG. 13 is a side elevation view thereof, the opposing side being a mirror image thereof;

FIG. 14 is an end elevation view thereof, the opposing end being a mirror image thereof; and,

FIG. 15 is a bottom plan view thereof.
